JEWELRY DISPLAY CASE

Howard Ferguson, Valley Cottage, N.Y., assignor to Bulova Watch Company, Inc., New York, N.Y.

Filed June 27, 1974, Ser. No. 483,616

Term of patent 7 years

Int. Cl. D9—03

U.S. CL. D9—233

FIG. 1.

FIG. 2.

FIG. 3.

FIG. 4.

FIG. 1 is a front perspective view of a jewelry display case in open position showing my new design;

FIG. 2 is a side elevational view with the display panel in a pivoted, closed position;

FIG. 3 is a front view thereof in closed position; and

FIG. 4 is a rear view thereof.

I claim:

The ornamental design for a jewelry display case, as shown.
